UNITED STATES PATENT OFFICE.

CARL J. PRINZLER, OF INDIANAPOLIS INDIANA, ASSIGNOR TO VONNEGUT HARDWARE COMPANY, OF INDIANAPOLIS, INDIANA, A CORPORATION OF INDIANA.

CONCEALED EMERGENCY-EXIT LATCH.

Application filed March 12, 1923. Serial No. 260,937.

There is at the present time a distinct tendency towards the utilization of all-metal doors in building construction, not only in storage and office buildings but also in buildings of the finer type, as for instance hotels, theatres, and even residences, and in many instances the scheme of decoration requires that, even though the door shall be latched in such position as to be readily yieldable in case of panic or fire, the latching mechanism shall be as unobtrusive as possible.

The object of my present invention is therefore to produce an emergency exit all-metal door structure of such character as to hide from view all elements of the latching mechanism excepting only the main actuating bar and its supporting plate.

The accompanying drawings illustrate my invention. Fig. 1 is a front elevation of an emergency exit door embodying my invention; Fig. 2 a vertical section at the middle plane of the latching mechanism; Fig. 3 an elevation, in partial vertical section, of the parts shown in Fig. 2; Fig. 4 a fragmentary vertical section adjacent one of the latches; Fig. 5 a plan of the parts shown in Fig. 4; Fig. 6 a fragmentary section below the plane 6-6 of Fig. 2; Fig. 7 a section on line 7-7 of Fig. 2.

In the drawings 10 and 11 indicate the inner and outer plates respectively, of a metal door, said plates being paneled as desired by depressed portions and secured together by channels 13, the channels forming the vertical edges of the door being arranged with their arms extending inwardly, while the channels at the upper and lower edges of the door are arranged with their arms extending outwardly, as indicated in Fig. 4, so as to form pockets for the reception of parts of the hidden latching mechanism now to be described.

The upper channel 13 near the free edge of the door is perforated at 14 to receive the main body of a latch casing 15 provided with laterally extended arms 16 which may be secured to the channel 13 by screws 17. Pivotally supported in casing 15 is a swinging latch bolt 18 connected by a link 19 with a lever 20 pivoted at 21 in casing 15 and connected by link 22 with a vertically sliding rod 23, the upper end of which is projected through a guide opening 24 formed in the lower end of casing 15. Similarly, at the bottom of the door, is a latch casing 30 which is projected through a perforation 14 in the lower channel 13. Casing 30 is provided with oppositely

extending arms 31, like arms 16, which are secured to the lower channel by screws 32. Pivotally mounted in casing 30 is a latch bolt 33 connected by a link 34 with the lower end of a rod 35 which is vertically slidable through and is guided by the perforation 36 in the upper wall of casing 30.

Secured to the lower end of rod 35 by a screw 40 is a tubular head 41 provided with a pair of laterally separated depending fingers 42 connected at their lower ends by a cross bar 43, the fingers 42 straddling a guide pin 44 which is part of the casing 45 in which the head 41 is slidably mounted. Slidably mounted in the lower end of casing 45 is a tubular head 50, similar to head 41 and to which the upper end of rod 35 is secured by screw 51. Head 50 is provided with a pair of laterally separated fingers 52, 52 connected by a cross bar 53 having a portion which overhangs and normally rests upon the upper face of the cross bar 43. The interior of casing 45 and the overlapped ends of the two heads 41 and 50 are covered by removable cover plate 55 held in place by a screw 56, the plate 55 having a perforation 57 opposite the overlapped portions of the two heads.

Projected through perforation 57 between fingers 52 beneath cross bar 53 and into engagement with the lower face of cross bar 43 is an operating lever 60 pivoted at 61 and guided between the ears 62 of an escutcheon plate 63 secured to the inner face of the door in the usual manner, the plate 10 of said door having a suitable perforation 64 through which the inner end of the lever may be projected and of sufficient size to permit the insertion of the casing 45 into the space between the two plates 10 and 11 of the door. Lever 60 at its exposed end is a downwardly and outwardly extending arm 60' to which are secured two tubular cross bars 66, 66, the opposite ends being secured to an arm 67 pivoted in the usual manner to a plate 68 secured to the face of the door, the bars 66 extending practically across the entire face of the door in the usual manner at a suitable height to be surely engaged by any one who should be forced in a panic against the inner face of the door.

There are times when it is desirable to put the latching mechanism out of commission and for that purpose there is threaded into one of the ears 62, eccentric to the pivotal axis 61, a locking pin 70 which may be driven into

a suitably placed pocket 71 formed in lever 60, as shown in Fig. 7, the outer face of the locking pin being provided with a pair of pockets 73 arranged to receive a suitably formed pin wrench.

5 In order to normally bias the lever 60 to extended position I provide a coiled spring 80 one end of which engages plate 63 and the other end engages a pin 81 on the lever 60, 10 the spring being retained in place by supporting it upon pivot 61.

Cross head 43 needs to be accurately placed relative to lever 60 and for that reason I secure to the inner face of plate 11 of the door, 15 opposite the perforation 64 of plate 10, a trough-like receiver 90 the upper edges of the side walls of which are outwardly flared as shown at 91 in Fig. 6. Casing 45 is also provided, at the upper edges of its side walls 20 with upwardly and outwardly flaring lips 92. Portions 91 are then provided with threaded perforations adapted to receive the clamping screws 93 which pass through slots 94 in the lips 92. The flaring arrangement of the 25 portions 91 and 92 permit easy access to screws 93 through perforation 64.

The construction and arrangement is such that pressure exerted upon bars 66 towards the face of the door will cause the inner end 30 of lever 60 to move cross bars 43 and 53 upwardly, thus retracting the latch bolts 18 and 33 and, because of the one-way connection between the two cross bars 43 and 53 and the one-way action of lever 60 on said cross bars, 35 the lower latch may be independently moved upwardly into the interior of the door so that in case the strike, which cooperates with the lower latch bolt 33, becomes filled with dirt, a proper functioning of the upper latch bolt 18 will not be interfered with.

40 It has been found in practice that the various moving parts of apparatus of this kind must be inspected from time to time in order to make sure that they are properly lubricated and in proper adjustment so that the 45 latch bolts may at all times properly cooperate with their strikes and at all times be properly yieldable to an actuation due to pressure exerted upon the cross bars 66 because the primary function of the apparatus is to insure 50 a proper yielding of the door outwardly in case of sudden need due to the existence of a panic within door's and it is for that reason that the various constructions and arrangements, to which attention has been called, 55 have been provided.

For instance, the formation of pockets in 60 the upper and lower edges of the door, by inversion of the channels 13, from their usual arrangement, is important because it then becomes possible to so mount the latch bolt casings 15 and 30 that they may be readily withdrawn, by removal of the screws 17, which are readily accessible from the edge of 65 the door, and withdrawal of the screws 40 and

51 which are readily accessible through the opening 64 when plate 63 is removed. The casing 45 is also readily accessible, either for removal as a whole from trough 90 by withdrawal of screws 93 accessible through opening 64, or by removal of screw 56 and plate 55 which are also accessible through opening 64. Yet all of this construction is entirely hidden so that the surface of the door is left free for such ornamentation as will harmonize 75 with the wall surfaces of the exterior and interior of the room.

It will be noticed that by placing the bolt-operating mechanism within the interior of the door it becomes possible, within the practical limits of operative leverages, to place the pivotal axis of the actuating lever 60 at the inner side of the escutcheon plate 63, instead of beyond the outer face of that plate as has heretofore always been necessary. As a consequence the external end 60' of the actuating lever 60 may be so formed and arranged that even when projected to its outermost position the cross bars 66 supported thereby do not lie as far from the inner face of the door as has heretofore always been found to be necessary and, when the cross bars are forced to their unlocking position and there locked by pin 70, the cross bars 66 lie practically against the inner face of the door.

The importance of this construction will become apparent when attention is called to the fact that the exit value of a door opening is determined by the amount of free space between the door jamb and the opened door, and of course this free space is determined by the amount of projection of the cross bar 66 from the face of the door. If now, there be say a theatre or auditorium in which one side wall contains ten pairs of exit doors a gain of one 105 inch in the amount of projection of the actuating bar will result in a saving of twenty inches in such an arrangement, thus making it possible to place an additional row of seats across the entire width of the auditorium 110 without in any way decreasing the exit value of the exits.

I claim as my invention:

1. An emergency exit structure comprising a swinging hollow metal door having 115 pockets in its upper and lower edges, and having an opening through one face plate giving access to the interior of the door at an intermediate point in its height, a pair of latch bolt casings mounted within the interior of the door, one in each of said pockets, means accessible from the exterior for detachably securing said latch bolt pockets in place, actuating elements for said latch bolts with their adjacent ends arranged opposite 120 the intermediate opening in the face of said door, means accessible through said opening and within the door, for guiding said actuating elements, connections between said actuating elements and the respective latch bolts 125 130

- whereby the weights of certain elements act to project the bolts, an externally accessible actuating member having a portion projected through said intermediate opening and into 5 independent one-way cooperative relation with each of said interior actuating elements, and a cover plate for said intermediate opening independent of the guides for the actuating elements, said cover plate forming a support for said externally accessible actuating element, and externally accessible means, independent of the guides for the actuating elements, for normally retaining the cover plate in place.
- 15 2. An emergency exit structure comprising a swinging hollow metal door having pockets in its upper and lower edges and having an opening through one face plate giving access to the interior of the door at an intermediate 20 point in its height, a pair of latch bolt casings mounted within the interior of the door, one in each of said pockets, means accessible from the exterior for detachably securing said latch bolt pockets in place, a vertically-25 arranged trough mounted within the door opposite the intermediate opening, a casing mounted in said trough, means accessible through said intermediate opening for vertically adjustably securing said casing to the trough within the door, a pair of latch-30 actuating heads slidably mounted in said casing and having a one-way overlapping interengagement, a cover plate for said intermediate opening, an actuating lever pivotally supported by said cover plate and having 35 one end projected through said intermediate opening and into a one-way engagement with said sliding heads, an externally accessible member carried by said actuating lever, and 40 connections between said sliding heads and the respective latch bolts.
3. An emergency exit structure comprising a swinging hollow metal door, a latch mounted within the door and projectable and retractable therefrom, an actuating lever having one portion projectable into the interior of the door and another portion exposed at the face of the door, a support for 45 said lever adapted to be secured to the face of the door, said support providing a pivotal mounting for the actuating lever parallel with and at a point between the faces of the door, and means actuatable by the inner end of the lever for retracting the latch bolt.
- 55 4. An emergency door retaining means comprising a latch-bolt housing and contained latch formed for mounting within the interior of a door between its faces, an actuating rod guided at one end in said housing, connections between said rod end and the latch such that the weight of the rod will normally project the latch, an independent guide structure adapted to be secured within the interior of a door, and in-60 jectible into said interior through an opening through one face of the door, a cover plate for said opening and withdrawable without disturbance of the guide structure, a head 70 slidably mounted in the guide structure, an actuating member, accessible from the exterior of the door, carried by the cover plate, an operative connection between said head and actuating member, and means, accessible through said opening, connecting said head and rod whereby the effective length of the 75 rod relative to the latch may be adjusted independent of the association between said head and actuating member.
5. An emergency door retaining means comprising a guide structure adapted to be 80 mounted in the interior of a door and injectible into said interior through an opening through one face of the door, a two-part latch-actuating member adapted to lie in the interior of a door, one part thereof being 85 slidably guided in the guide structure, a cover plate for said opening, an external actuating member carried by said plate and cooperating with the guided element of the two-part member, and a connection accessible through said 90 opening between the two parts of the two-part member of such character that the effective length of said two-part member may be adjusted without regard to the coactive relation between said two-part member and the 95 external actuating member.
6. An emergency door retaining means comprising a guide structure adapted to be 100 mounted in the interior of a door and injectible into said interior through an opening through one face of the door, a two-part latch-actuating member adapted to lie in the interior of a door, one part thereof being 105 slidably and non-rotatively guided in the guide structure, a cover plate for said opening, an external actuating member carried by said plate and cooperating with the guided element of the two-part member, and a connection accessible through said 110 opening between the two parts of the two-part member of such character that the effective length of said two-part member may be adjusted without regard to the coactive relation between said two-part member and the external actuating member.
7. A structure of the character defined in claim 6 wherein the two parts of the two-part member are telescoped together and a retaining screw accessible through the opening in the face of the door serves to hold the two 115 parts in adjusted relation.
8. An emergency door retaining device comprising a perforated cover plate formed for attachment to the inner face of a door over an opening through said face, an ear 120 carried by the under face of said plate adjacent the perforation, an L-shaped actuating lever having one arm projected through said perforation, a pivotal connection between said arm and ear parallel with the plane of 125
- 65 70 75 80 85 90 95 100 105 110 115 120 125 130

- the cover plate and intermediate the length of the arm, and a hand-bar carried by the outer depending arm of the L-shaped lever and parallel with the plane of the cover plate.
- 5 9. An emergency door retaining device comprising a guide structure adapted to be mounted in the interior of a door and injectible into said interior through an opening through one face of the door, a latch-actuating element slidably mounted in said guide structure, a base trough adapted to be secured to the inner face of a face forming element of the door and slidably associated with the guide structure, and means accessible through the said opening for holding the guide structure in adjusted position in the base trough. ¹⁵
- In witness whereof, I have hereunto set my hand at Indianapolis, Indiana, this 9th day of March, A. D. one thousand nine hundred and twenty-eight.

CARL J. PRINZLER.
